UNITED STATES PATENT OFFICE.

HARRY W. REUTER, OF KANKAKEE, ILLINOIS, ASSIGNOR OF ONE-HALF TO JOHN S. BURTON, OF CHICAGO, ILLINOIS.

COMBINED RADIATOR SHIELD AND HUMIDIFIER.

Application filed September 16, 1922. Serial No. 588,563.

To all whom it may concern:

Be it known that I, HARRY W. REUTER, a citizen of the United States, residing at Kankakee, in the county of Kankakee and State of Illinois, have invented a certain new and useful Combined Radiator Shield and Humidifier, of which the following is a specification.

The invention pertains to a combined shield and humidifier for radiators, and has for its general aim the production of such a device, which is capable of manufacture at a low cost and of being quickly and easily applied to or removed from a radiator.

15 A further object is to provide a device of this character which presents a neat and ornamental appearance.

Still another object is to provide a construction whereby the humidifier may be conveniently replenished with water from time to time.

In the accompanying drawings, I have shown but one form of the invention. It is contemplated, however, that various changes 25 in the form, construction and arrangement of parts may be made by those skilled in the art without departing from the spirit and scope of the invention, as expressed in the appended claims.

30 Figure 1 is a perspective view of my improved radiator attachment in use.

Fig. 2 is a fragmentary vertical sectional view through the device.

Fig. 3 is a horizontal sectional view taken 35 in the plane of line 3 of Fig. 2.

Fig. 4 is a transverse sectional view taken substantially in the plane of line 4 of Fig. 2.

The device comprises a frame including a 40 pair of end members or brackets 7 which are connected together by a pair of spaced parallel bars 8. The upper edges of the brackets are provided with inturned portions or lugs 9 through which screws 10 are entered to secure the ends of the bars in place upon the brackets. The bars rest upon 45 the upper ends of the coils A of the radiator, as shown in Fig. 2.

11 indicates angular brackets welded or otherwise secured upon the under sides of 50 the bars 8, which are also preferably angular in form. The upright brackets 11 project above the bars 8 and support a water pan 13, there being two pairs of said brackets 11, one pair near each end of the pan.

55 The latter is provided at its opposite longi-

tudinal edges with hooked flanges 14 adapted to seat upon the upper edges of the brackets, and the pan is thereby held out of contact with the radiator.

The device may be secured to a radiator 60 in any preferred way. Preferably, I employ hook members 15 carried by cross-pieces 16 of the frame. Said cross-pieces may be secured to the under sides of the brackets 11 as by welding. The lower ends of the members 15 are bent to form hooks adapted to engage the rods B which are employed to connect the coils of the radiator together in a well known way. The upper ends of the hook members are flanged and provided with 65 threaded apertures to receive screws 17 depending from the cross-pieces 16. It will be apparent that by tightening the screws 17, the device will be held firmly in place upon the top of the radiator. 70

A cover 18 for the device is hinged at 75 upon the rear ends of the cross-pieces 16. This cover is in the form of a hood having depending flanges. It constitutes the top of a shield which prevents the direct 80 upward passage of currents of heated air from the radiator and serves to direct such air currents across the surface of the water in said pan. It also serves as a cover for the humidifier.

The hinge devices may be of any suitable character. Preferably they comprise simply a hinge plate 20, one end of which is secured upon the inner side of the depending rear flange of the cover, the opposite 90 end being free so as to permit of the swinging movements of the cover. Intermediate its ends, the hinge plate extends through a slot 21 in the rear end of the cross-piece 16, and is bent to form a hump of U-shape which 95 engages with the rear end of the slot 21 when the cover is swung upwardly and rearwardly. The free end of the hinge plate 20 in this operation moves from a depending position in contact with a depending portion 16a of the cross piece 16, into engagement with the underside of the cross piece forwardly of the slot 21, thus limiting the rearward movement of the cover. Such rear position of the cover is shown 100 in broken lines in Fig. 4. It will be observed that this construction permits of the bodily detachment of the cover at will, and simplifies the assembling of the parts.

The back of the shield is formed by a 110

plate 22, which in the present instance is secured in position by end flanges 23 fastened near their upper ends to the rear vertical portions of the end brackets 7. The upper edge of the back plate may overlap the downturned portions 16^a of the cross-pieces 16 and be secured thereto by means of screws 23^a.

It will be apparent that I have produced a radiator attachment of a simple construction, neat in appearance, and effective as a humidifier and shield. The device may be quickly and easily applied, and the cover may be readily manipulated to an open position to enable the water pan to be filled. Such hinging of the cover is advantageous inasmuch as it materially facilitates the filling operation. The cover is positioned to provide for the free circulation of heated air above the water pan.

I claim as my invention:

1. The combination with a radiator, of a frame comprising bars adapted to rest upon said radiator and end members connecting said bars, means for securing said frame rigidly to the radiator, a water pan, members on said frame supporting said water pan above and out of contact with said radiator, and a cover for said water pan supported by said frame and positioned to provide for the free circulation of air above said pan.

2. A radiator attachment comprising, in

combination, two parallel bars adapted to rest on the top of a radiator, a pair of brackets connecting the ends of said bars, cross pieces secured to said bars, means for clamping said bars rigidly to a radiator, a plurality of upright members carried by said parallel bars, a water pan removably supported above the radiator on said upright members, and a removable hood or cover supported by said cross pieces and adapted to provide for free circulation above said pan.

3. A radiator attachment comprising, in combination, a frame including two parallel bars adapted to rest on the top of a radiator, and a pair of cross pieces fastened to said bars, and having slots near their rear ends, means for clamping said frame rigidly to a radiator, a water pan, means carried by said frame for supporting said water pan above the radiator, a box-like cover, positioned to provide for free circulation above the pan, two plates extending through the slots in said cross pieces, one end of each of said plates being fastened to the depending rear side of said cover and the other end being adapted to engage with said cross pieces so as to limit the backward swing of said cover.

In testimony whereof, I have hereunto affixed my signature.

HARRY W. REUTER.
